[57] CLAIM

The ornamental design for combination lawn ornament and cremation container, as shown and described.

DESCRIPTION

FIG. 1 is a front perspective view of a combination lawn ornament and cremation container showing my new design;

FIG. 2 is a top view thereof;

FIG. 3 is a front view thereof, the rear view being a mirror image thereof;

FIG. 4 is a left side view thereof, the right side view being a mirror image thereof;

FIG. 5 is a bottom view thereof;

FIG. 6 is a front perspective view of a second embodiment of a combination lawn ornament and cremation container showing my new design;

FIG. 7 is a top view of the embodiment of FIG. 6, the front view appearing as shown in FIG. 3, the rear view being a mirror image of FIG. 3, the left side appearing as shown in FIG. 4, the right side being a mirror image of FIG. 4; and, FIG. 8 is a bottom view of the embodiment of FIG. 6.
